UNITED STATES PATENT OFFICE.

DAVID S. HULFISH, OF TORONTO, ONTARIO, CANADA.

PRINTING-TELEGRAPH SYSTEM WITH WAY STATIONS.

Application filed October 15, 1926. Serial No. 141,778.

This invention pertains to printing telegraph systems of the synchronous multiplex type.

The object of this invention is to operate, 5 by printing telegraph, waystations which have a low volume of traffic, using a minimum of equipment at each waystation, and imposing at each waystation a minimum burden of electrical constants in the line circuit. 10 The manner in which this object is accomplished is (a) to provide a main-line circuit from a first station or head office and extending through waystations to a terminal which may or may not be another "head office"; 15 (b) to provide a sole winding of a sole line relay in that circuit at each waystation; (c) to make all local automatic functions at the waystation dependent upon that relay and controlled by it; (d) to cause to flow in that 20 circuit a signaling current primarily under control of the head office and secondarily modified by control of any waystation; (e) to transmit intelligence by printing telegraphy from the head office to any waystation 25 by modifications in that current, such modifications originated at the head office and controlled solely at the head office; (f) to transmit intelligence by printing telegraphy from any waystation to the head office by modifications of that current, such 30 modifications controlled jointly by the waystation and the head office; (g) to provide signal-sending means for service-signals in connection with a waystation receiving device 35 and controlling signal-receiving means at the head office, whereby the head office when sending a message to a waystation may receive a response-signal and thereby be advised that the waystation receiving device is 40 operating in response to the head-office control; (h) to send a message to a waystation and to receive a message from the same waystation at the same time without interference; (i) to send a plurality of messages to 45 sundry waystations, and to receive a plurality of messages from sundry waystations, all at the same time and without interference, together with the response-signaling according to "(g)" from each receiving waystation 50 independently; (j) to provide for making waystation modifications in the line current between successive signals as made by the head-office signal devices, whereby unitary signals of polar and neutral or strength nature may be coincident and simultaneous; 55 (k) to provide a system of phase correction

effective to correct the phase of a distributer throughout a maximum angle; (m) to operate by a sole distributer brush all of the functions of receiving, sending, synchronizing and response-signaling at the waystation; (n) to provide means for preventing interference between waystations; (o) to provide a starting cam with contacts interchangeably used for charging the starting magnet of the sender and for charging the starting magnet of the printer; (p) to provide a service channel into the head office and out of the head office by which control of the waystations may be effected apart from the 60 control of the message channels, together with supervision of the message channels; and (q) to supply all line currents for any line from a single source located at the head 65 office.

In the drawings, Fig. 1 shows circuits for a system of one line comprising a head office and three waystations and terminal earth connection; Fig. 2 shows a modification of the circuits for the head office; Fig. 3 shows 70 circuits for a waystation; and Fig. 4 shows detail for another waystation.

The invention is exemplified herein by a system of polarity-and-strength duplex or 75 diplex working, in which the head office supplies a continuous current which is varied in two characteristics, being (1) reversed in polarity by the senders at the head office to signal the waystations by polar control, and being (2) varied in strength by the senders 80 at the waystations by effect of including or removing resistance in the line circuit to signal the head office by neutral control. Polar channels A, B, C are used for messages from the head office and polar channel D is used 85 for synchronizing; neutral channels A, B, C are used for messages to the head office and neutral channel D is used for response signaling.

Referring to Fig. 1: The sending distributer 10 serves four channels, of which A, B, C are served also by the senders 11, 12, 13, and of which the channel D has its first four points, 14, 15, 16, 17 connected to negative battery N, and its last point 18 connected to positive battery P, thus providing a polarity reversal for phase correction of the waystation distributers as 44.

The line circuit comprises a battery, P or N; the senders; the distributer 10; the wire 19; the marginal, neutral, receiving relay 20; waystations 21, 22, 23; and the line wire 24;

in sections, connecting in sequence its head office, its waystations and its terminal earth. In this line circuit, a line current flows continuously, as modified by the senders of the system. If the terminal earth of the line wire 24 be in the same office with the distributor 10, then the neutral relay 20 may be in either end of the line circuit, as indicated by dotted symbol 20 in Fig. 1.

10 The head office sending equipment is included in the line circuit as traced above. Polar channel A (sending from head office) comprises sender 11 and waystation 21, and it is associated with response-signal devices 15 of signal-point 34 in the distributor. Polar channel B comprises sender 12 and waystation 22, and its response-signal is over signal-point 35. Polar channel C comprises sender 13 and waystation 23, and its response-signal is over signal-point 36.

The head office receiving equipment comprises the relay 20, the distributor 30, the printers or recorders, 31, 32, 33, and the three response-signal sets, each comprising 25 a polar relay as 38 and a signal as 37, the three relays connected respectively to points 34, 35, 36 and controlling the three signals respectively.

The differential relay 20' and balancing 30 network 25 of Fig. 2 may be substituted for the marginal relay of Fig. 1.

Referring to Fig. 3: The equipment of the waystation 21, connected to polar channel A and neutral channel C, is shown. The line 35 relay 40 responds to P current from distributor 10 and places earth upon wire 41 for messages and upon wire 42 for synchronizing. The brush 43 of the distributor 40 will gain (or lose) phase as compared with the brush of distributor 10, until the brushes are in phase on points 45 and 18 respectively, after which the break relay 46 and the phase corrector magnet 47 will maintain synchronism.

45 All of the brushes of the line operate in synchronism, and while all brushes are on channel A the relay 40 and the brush 43 will record upon the printer 48 all signals sent from sender 11.

50 While all brushes are on channel C, the relay 20 and distributor 30 will record upon printer 33 all signals sent from sender 49. The manner of sending signals from the sender 49 to the relay 20 is as follows: The 55 cam 50 on distributor shaft 51 moves in phase with brush 43. Its low-radius arc 52 permits cam-controlled shunt points 53 to open while brush 43 is upon the points of channel C in distributor 44. With the shunt 60 53 open, the sending line-resistance 54 is shunted by the path comprising wire 55, wire 56, brush 43, contacts in sender 49 and wire 57. With a perforated tape in the sender 49, selected points in the sender 49 65 will be open by the tape code, and when the

brush 43 engages such an open sender-point, all the shunts of the resistance 54 will be open, and the sending resistance 54 without shunt will be included in the line circuit, the line current will be decreased and the marginal (or differential) relay 20 (or 20') will operate its armature. This will connect P battery to the corresponding wire into the printer 33 and the signal of the sender 49 will be recorded. This will be effected (over 70 neutral channel C) even though the head office may be sending at the same time to waystation 23 (over polar channel C) or to waystation 21 (over polar channel A). Nor will there be any interference if the six 80 channels shown, three polar and three neutral, all operate at the same time.

Because all brushes of the line are in synchronism, all unitary signals will be in synchronism, and the polar changes in the line 85 current will occur simultaneously with the strength changes in the line current. By this simultaneous synchronism, a reversal of polarity in the line current may not occur during the continuance of a unitary strength 90 signal.

The synchronizing circuits are the same in all waystations.

The mechanical devices of the several waystations are alike except the cams 50, 95 which are cut variably. Each such cam 50 has two low-radius arcs (contiguous in Fig. 1) the arc 52 for opening the shunt points 53 during the sending interval, and the arc 58 for opening the shunt points 53 during 100 the response-signal interval. The cam 50' of Fig. 4 is cut for station 23, which sends on channel B and which reports the operation of its printer by a response-signal on the third time unit of neutral channel D. 105

The receiving and sending connections vary at the several waystations. At waystation 21, the printer 48 is connected to the signal-points of channel A and its starting magnet 64 is connected to points 61 to be 110 closed by cam 60 immediately after the distributor brush 43 has left channel A. At station 22, the printer is connected to the points of channel B and its starting magnet is connected to points 62 to be closed by cam 115 60 immediately after the distributor brush has left channel B. At station 23, the printer is connected to the points of channel C and its starting magnet is connected to points 63 to be closed by cam 60 immediately 120 after the distributor brush has left the channel C. At station 21, the sender 49 is connected to the points of the channel C and its starting magnet 59 is connected to points 63 to be closed immediately after the distributor 125 brush 43 has left the channel C. At station 22, the sender is connected to the points of channel A and its starting magnet is connected to the points 61 to be closed by the cam 60 immediately after the distributor 130

brush has left the channel A. At station 23, the sender is connected to the points of channel B and its starting magnet is connected to the points 62 to be closed immediately after the distributor brush has left the channel B. Thus the points, 61, 62, 63 are used alternatively for the starting magnet of the printer or for the starting magnet of the sender according to the line channels 10 serving the station.

Every impulse from cam 60 to the starter magnet 64 charges also the reporting relay 65, which has an armature retarded sufficiently to be retained continuously when 15 an impulse is received for every revolution of the distributor shaft 51. The points of relay 65 are connected respectively to wire 57 and to point 67 in the distributor 44. The distributor point 66 is connected by wire 68 20 to wire 55. With printer 48 not operating and with all brushes on the first time unit of channel D, the cam 50 of station 21 opens the shunt points 53 by effect of its low-radius arc 58; the resistance 54 is shunted 25 by the path, wire 55, wire 68, point 66, brush 43, point 67, wire 70, points of uncharged relay 65, wire 69 and wire 57; the line current remains "strong," relay 20 does not move 30 its armature, and gives N battery to relay 38; the lamp 37 remains dark. With printer 48 operating repeatedly relay 65 retains its points open continuously, and at each repetition of the first time unit of channel D, all shunts of the resistance 54 are open, the line 35 current is decreased, and relay 20 (or 20') operates its armature to give P battery to relay 38, which closes its points, and lamp 37 glows continuously. At waystation 22, the wires 68 and 70 are connected to the 40 points of the second time unit of channel D; and at waystation 23 the wires 68 and 70 are connected to the third points of channel D.

Should the head office, on operating the sender 11, note that a signal is not received 45 on lamp 37, the deduction may be that the waystation 21 is not in phase. With the head-office distributor running 200 revolutions per minute and the waystation motor running 201 R. P. M., the brush 43 will require one minute for a maximum correction. The head office may await synchronism by chance or may expedite it by stopping all 50 polar channels for that length of time, when transmission may be resumed and the response-signal should be received on the lamp 37.

The total function of the cam 50 is to remove the line resistance 54 from the control of other equipment of its waystation 55 during the time intervals when the line is reserved for the use of other waystations, and to subject the line resistance to the control of the sender when the line is reserved for the use of that sender. By the cam 50, but one line resistance as 54 may be in-

cluded in the line circuit at any one time, even though two or more waystations may be sending messages to the head office.

Having thus described my invention, what I claim is:

1. A printing telegraph system, comprising a polar sender; a strength sender located remotely from said polar sender; a polar receiver; a strength receiver; a line-circuit; and a sole source of polar line-currents serving the system. 75

2. A duplex printing telegraph system, comprising a first sender; a first receiver; a second sender; a second receiver; a line-circuit and a sole source of line-currents; 80 said first sender for modifying one characteristic of the line-current and said second sender for modifying another characteristic of the line current, said senders remote from each other and one of said senders remote 85 from said source.

3. In a printing telegraph system, a head office; a sending distributor at said head office; a line; polar senders controlling transmission channels through said distributor; waystations; distributors at said waystations controlled by currents in said line; means, at said head office solely, for producing currents in said line; strength senders at said waystations for modifying the 90 strength of the currents produced in said line by said means the polarity of the currents having been determined by said polar senders; and strength-signal receiving devices at said head office. 95

4. In a printing telegraph system, a head office; polar senders at said head office; a sending distributor at said head office; a line; waystations; polar distributors and printers at said waystations; means at said 100 head office only for producing line currents in said line; strength senders comprising variable series line resistances at said waystations to modify the strength of the line-currents whose polarity has been determined 105 by the polar senders at the said head office; and a strength receiver at said head office. 110

5. In a printing telegraph system, a first station; a second station; a line-circuit connecting them; a source of potential to produce in said line-circuit a line-current having a predetermined direction of polarity; a source of potential to produce in said line-circuit a line-current having the reversed direction of polarity; a polar sender at said 115 first station, said sender combined with both of said sources of potential to constitute a sole source of polar line-currents in said line-circuit; a polar receiver; a strength sender for varying the strength of the polar line-currents in said line-circuit; and a strength receiver. 120

6. In a printing telegraph system, a head office; a waystation; a line-circuit connecting them; a sole source of line-current; a 130

1. In a printing telegraph system, a polarity-changing sender at said head office; a polar line-relay at said waystation; a resistance-changing sender at said waystation; and a neutral relay at said head office; all 5 co-operating to produce duplex transmission using current from a single source varied in two characteristics.
2. In a printing telegraph system, a first station; a plurality of distant stations; a 10 line; a sole source of line-current; means for transmitting from said first station to a distant station by polarity control; and means for transmitting from a distant station to said first station by strength control of currents from said sole source.
3. In a printing telegraph system, a first office; a second office; sending means at said first office; receiving means at said second office, and a signal-receiving device at said 15 first office and operated by said receiving means.
4. In a printing telegraph system, a first office; other offices; a line-circuit connecting said offices; a sender at said first office; receiving devices in said other offices responsive to said sender; means associated with each said receiving device for sending a signal when said receiving device is operating; and signal devices in said first office responsive to said means, one for each of said other offices.
5. In a printing telegraph system, a first office; a second office; a line circuit connecting said offices; a source of current in said 20 line circuit; a sender in said first office; a receiving device in said second office and responsive to said sender; means in said receiving device for modifying the currents in said line circuit when said receiving device is operating; and a signal in said first office responsive to said means.
6. In a printing telegraph system, a line-circuit; a source of current in said line circuit; a polar sender and a polar-controlled 25 receiver connected by said line circuit; a strength-controlling device in said receiver and a strength-responsive device at said sender and connected by said line circuit.
7. In a printing telegraph system, a first station; a plurality of distant stations; a line; a sole source of line-current; means for transmitting from said first station to a distant station by polarity control; and means for transmitting from a distant station to said first station by strength control of currents from said sole source.
8. In a printing telegraph system, a first office; a second office; sending means at said first office; receiving means at said second office, and a signal-receiving device at said 30 first office and operated by said receiving means.
9. In a printing telegraph system, a first office; other offices; a line-circuit connecting said offices; a sender at said first office; receiving devices in said other offices responsive to said sender; means associated with each said receiving device for sending a signal when said receiving device is operating; and signal devices in said first office responsive to said means, one for each of said other offices.
10. In a printing telegraph system, a first office; a second office; a line circuit connecting said offices; a source of current in said 35 line circuit; a sender in said first office; a receiving device in said second office and responsive to said sender; means in said receiving device for modifying the currents in said line circuit when said receiving device is operating; and a signal in said first office responsive to said means.
11. In a printing telegraph system, a line-circuit; a source of current in said line circuit; a polar sender and a polar-controlled 40 receiver connected by said line circuit; a strength-controlling device in said receiver and a strength-responsive device at said sender and connected by said line circuit.
12. In a printing telegraph system, a recording device; signaling means in said recording device; and means for rendering said signaling means operative when said recording device is operating.
13. In a printing telegraph system, a sender; a signal at said sender; a receiver; and means at said receiver for operating said signal.
14. In a printing telegraph system, a line; a station; a distributor of multi-channel type at said station; a recorder at said station 55 associated through said distributor with one of the channels of said line; a sender at said station associated through said distributor with another of the channels of said line; and a sole brush in said distributor serving both said sender and said recorder.
15. In a synchronous-multiplex telegraph system, a distributor; a brush in said distributor; a line; a sender; and a recorder, said sender and said recorder alternately 60 connected to said line by said brush.
16. In a printing telegraph system, a combination distributor for a receiving channel and for a sending channel; a brush in said distributor, said brush serving both channels 65 alternately.
17. In a printing telegraph system; a combination distributor serving a plurality of channels in rotation; a sole brush in said distributor and serving a receiving channel and a sending channel alternately.
18. In a printing telegraph system, a line; a sole source of current in said line; a plurality of resistances in said line; a distributor with each of said resistances; a sender with each of said resistances for sending signals over said line by varying its associated resistance; and a disabling device for each of said resistances, all of said disabling devices cooperating to enable said resistances to function one at a time.
19. In a printing telegraph system, a line; a plurality of waystations connected to said line; sending resistances; a sending-resistance shunt at each waystation; said shunts 95 cooperating to shunt all but one of said sending resistances at all times.
20. In a printing telegraph system, a plurality of waystations; distributors at said waystations; senders at said waystations; a plurality of sender-disabling means at said waystations, said several disabling means cooperative to disable all said senders but one at all times.

DAVID S. HULFISH.
